UNITED STATES PATENT OFFICE.

EMANUEL FOUREMAN, OF ARCANUM, OHIO.

RAILROAD-TIE.

1,115,464.

Specification of Letters Patent. Patented Oct. 27, 1914.

Application filed June 20, 1914. Serial No. 846,297.

To all whom it may concern:

Be it known that I, EMANUEL FOUREMAN, a citizen of the United States, residing at Arcanum, Darke county, State of Ohio, have invented certain new and useful Improvements in Railroad-Ties, of which the following is a specification.

My invention relates to railway ties and more particularly to a concrete tie.

10 The object of the invention is to also provide improved means for securing and supporting the ties and anchoring the supporting means in place on the tie.

Another feature of the invention is the 15 improved form by means of which the tie is molded in place.

Other objects and the novel features of the invention will be apparent from the following description, taken in connection with 20 the drawing, in which,

Figure 1 is a side elevation of the tie showing the rails supported on it. Fig. 2 is an end elevation of the tie, with a portion of a rail shown in side elevation. Fig. 3 25 is a top plan view of the tie and parts of the rails thereon. Fig. 4 is a longitudinal section of the tie and the rails thereon. Fig. 5 is a cross section of the tie on the line 5-5, of Fig. 3. Fig. 6 is a plan view of the 30 form in which the tie is molded. Fig. 7 is a side elevation of the same.

The tie 10 comprises a casting of cement, concrete or the like, which may be molded in place in the roadbed while the road is in 35 operation. It is substantially rectangular in longitudinal and transverse cross-section and on its top supporting surface it has the shoulders 11, 11 near its opposite ends which prevent the spreading of the rail as will appear. The mold, as is shown in Figs. 6 and 40 7, has the parallel sides 12 and 13 provided with eyes 14 on the outside thereof to receive the hooks 15 at the projecting ends of the end members 16 and 17. The end members 16 and 17 are notched as at 18 to receive 45 the ends of the side wall members 12 and 13. At their inner sides the walls 12 and 13 each have a pair of vertical shoulders 19 and 20, the shoulder 19 being nearer one end of the 50 wall than the shoulder 20 is to the other. Each side wall has the shoulders 21 at its upper edge to correspond with the shoulders 11, 11 of the tie. The section of the tie between the pairs of shoulders 19, 20 is thinner 55 since the section of the wall extends inwardly to form the shoulders 19, 20. By

releasing the hooks 15 the ends 16 and 17 of the mold may be removed, which also permits the removal of the side walls of the form. Near the lower edge of the side walls of the form and extending diagonally therethrough adjacent the shoulders 19 and 20 are holes 22 which when the form is set up will be diagonally in line to receive a pin or bar for suitably carrying the metal lining 60 tube 23 of the tie.

When the tie is to be planted in the roadbed, a trench is dug and the form is set accurately in place transversely of the track. The tube 23 is held in place by a bar fitting 70 opposite pairs of holes 22. The concrete is filled in and as soon as it has set the form is taken down and removed. The tube 23 is then held in place by the concrete and forms a lining for the hole 22' extending 75 therethrough.

To lock the rails R, R in place, I employ the following devices: A pin or headed bolt 25 is passed through the tube 23, the head 26 thereof holding it at one end and a cotter pin 27 passing through an opening therein at the other end. The bolt 25 passes through the eyes of eyebolts 28, the shanks of which are threaded to receive securing nuts 29. Between the eyebolts and the head 26 and locking pin 27 I place metal angle washers 30 and 31.

The foot of the rail R fits in a longitudinal channel 32 in the tieplate 33, the under side of which is recessed as at 33' to receive an asbestos or other antifriction pad 34 which fits in a pocket between the tieplate and the tie. As is shown, the top of the tieplate extends beyond the longitudinal faces of the tie and is beveled so that 95 its base is the same width as the tie.

Clamping irons 35, 35, which have parts fitting the top surface of the foot of the rail are secured in place to the tieplate 33 at one end by the nuts 29 on the threaded 100 end of an eyebolt, the shank of the latter extending through the tieplate and the clamping iron. The other end of each clamping iron is held in place by short bolts or fastening devices 36 which pass through the tieplate and clamping iron only.

It will be seen that the fastening means comprises a rod 25 which fits in a tube 23 embedded in the concrete tie and extends transversely of the tie diagonally under 110 each rail. The rails are anchored to the rods passing through the tubes by the eye-

bolts 28, the tieplates 33 and clamping irons 35.

I do not wish to be limited to the exact details as shown and described as changes 5 may be made without departing from the spirit of the invention.

Having thus described the invention, what is claimed and desired to be secured by Letters Patent is:

10 1. In a railway tie, the combination of a concrete body having tubes embedded therein and extending diagonally under said body, and means for securing the rails to the tie, said means comprising parts which 15 extend through said tubes.

2. A concrete railway tie having tubes embedded therein and extending transversely thereof, means for securing the rails to the tie, said tubes extending diagonally 20 underneath the rails, said means comprising members which extend through the tubes, and devices connected to said members for clamping the rails.

3. A railway tie having shoulders and 25 tubes extending transversely thereof, means

for securing the rails in place on the tie comprising rods extending through said tubes, tieplates on which the rails rest, said shoulders limiting the movement of the tieplates, members for securing the tieplates 30 to said rods, and devices for clamping the rails to the tie plates and held in place by said members.

4. Rail supporting and securing means comprising a concrete supporting body, a tube 35 embedded therein and extending transversely thereof, a plate resting on the supporting body, means on the plate for clamping the rail, a rod extending through said tube, devices connected to the ends of 40 said rod, and means coöperating with said devices to hold said clamping means and plate in place.

In testimony whereof I affix my signature in presence of two witnesses.

EMANUEL FOUREMAN.
